UNITED STATES PATENT OFFICE

JOSEPH E. RUTTER, OF FORT LEE, NEW JERSEY

FURNACE FOR BURNING LIQUID FUEL

Application filed June 16, 1927. Serial No. 199,180.

This invention relates to an apparatus or furnace for the efficient burning and gasifying of liquid fuel or oil for heating purposes, and has for its object the provision of a 5 hydro-carbon burner which will operate at high efficiency and at a minimum cost; and the invention consists of the improved construction and arrangement of parts which will be described in detail in the specification to follow, and the novel features of 10 which will be set forth in the appended claims.

In the accompanying drawings:

Fig. 1 is a front elevation of my improved 15 apparatus with parts broken away and parts in section.

Fig. 2 is a side elevation of the same with parts broken away and with parts in section.

Fig. 3 is a fragmentary view in elevation 20 of the apertured arch of the secondary combustion chamber.

Fig. 4 is an elevation of the oil ignition 25 burner unit.

Fig. 5 is a plan view of the same.

Fig. 6 is a vertical section through one 30 side of the burner unit on the line 6—6 of Fig. 5.

Referring to the drawings:

The improved apparatus comprises as its 35 main elements an ignition burner unit 1 to which the liquid fuel, in the present instance fuel oil is supplied by a pipe 2, an expansion chamber 3 arranged over the ignition burner 40 of the burner unit, a primary combustion chamber 4 arranged over and connecting with the expansion chamber, and a secondary combustion chamber 5 communicating with and surrounding the primary combustion 45 chamber, the said elements being surrounded by and enclosed in a heating chamber 6 of a furnace structure provided with side walls 7, a rear wall 7^a, and a front wall 8.

The ignition burner unit as best shown in

Figs. 4, 5 and 6 consists of a body of truncated conical form which is seated on the bottom of an open rectangular tray 9 so as to be surrounded by the side walls 9^a of said tray. At the top of the conical body is an

oil distributor, in the form of a pan 10 in

position to receive the oil flowing from the discharge end of the oil supply pipe 2, which pan is formed with discharge openings 11, in the present instance four in number in its sides, arranged at equal intervals around the pan, so as to cause the oil delivered to the pan and unignited therein to flow down the inclined side of the conical body. The outer side of the conical body is formed, in line with the discharge openings 11, with grooves or channels 12 which extend from said discharge openings to the base of the body, and in these channels are arranged at two points in their length upper and lower protuberant spherical-like deflecting members 13 and 14 for the purpose of dividing and spreading laterally the streams of oil flowing downwardly in the channels. At the points in the channels where the deflecting members 13 are located the conical body 55 is formed with upwardly and outwardly extending branch channels 15 communicating at their lower ends with the channels 12; and at the points where the lower deflecting members 14 are located, the conical body is 60 formed with similar branch channels 16 communicating at their lower ends with the bases of the channels 12. Surrounding the conical body just below the deflecting members 13 is a circular air distributing pipe 17 65 formed with air discharge openings 18 in its inner side in line with the respective channels 12, the said pipe extending outwardly through a side wall of the tray 9 and being adapted to be connected with a suitable source of air under pressure, and being provided with a controlling valve 19; and surrounding the conical body just below the deflecting members 14 is a similar circular air distributing pipe 20 formed with air discharge openings 21 in its inner side in line with the respective channels 12 said pipe extending outwardly through the side wall of the tray and being adapted for connection with a suitable source of air under pressure 70 and provided with a controlling valve 22.

In the operation of the burner unit the oil is fed by gravity by the supply pipe to the distributing pan 10, where it is ignited, and such oil as may not become ig- 75 80 85 90 95 100

nited in the pan flows through the discharge holes therein down the channels 12. This oil is met by the currents of air from the distributing pipe 17 and is blown by said air currents against the protuberant deflecting members 13 and up the branch channels 15 and is vaporized, and such oil as is not vaporized will continue down the channels 12 where it will be met by the air jets from the pipe 20 by which the oil will be blown against the protuberant deflecting members and up the branch channels 16 and vaporized, and any oil which is still unvaporized at this point will flow down to the bottom of the tray and escape therefrom through openings 23 in the side wall of the tray and enter a pipe 24 by which the oil will be delivered to an overflow tank 26 more particularly described later on.

20 Due to the action of the air currents on the oil flowing down the channels 12, the oil is broken up into a finely divided vaporized condition or spray and will readily ignite and burn with efficient combustion. As the oil which is still unvaporized will instantly escape from the tray, there will be no liability of the oil boiling in the tray and no chance for the formation of carbon at this point.

30 The expansion chamber 3 is in the form of a throat with upwardly and outwardly flaring walls and is arranged with its lower end close to the upper end of the tray 9 and is supported by a floor 27 of heat insulating brick extending horizontally between the walls of the heating or furnace chamber 6 before alluded to. The walls of the expansion chamber are formed of carborundum possessing in high degree the property of radiating heat and the burning oil passing upwardly therethrough to the primary combustion chamber will be effectively expanded.

40 The primary combustion chamber 4 is arranged over the expansion chamber 3, in position to receive the burning oil directly therefrom, and is enclosed at its sides by side walls 28 rising from the floor; at its back by a back wall 29 also rising from the floor, which walls are formed with a multitude of restricted apertures 30 and 31 respectively; at its front by the wall 8 before alluded to; and at its top by a solid arch 32, the said walls and arch being preferably formed of carborundum brick, and the heated arch serving as a target against which the burning particles of oil from the expansion chamber are impinged.

50 The burning vaporized oil escaping through the apertures in the back and side walls of the primary combustion chamber will flow into the secondary combustion chamber 5, which as before mentioned surrounds the primary chamber. This secondary chamber is enclosed at its sides and back

by side piers 33 and a back wall 34 rising from the floor 27, and at its top by an arch 35, which walls and arch are preferably formed of carborundum, the said chamber being closed at its front by the front wall 8 of the furnace structure. The rear wall is provided at a point above the arch of the primary combustion chamber with apertures 36 and the arch 35 is provided with apertures 37, through which two sets of apertures the burning oil passes to the heating chamber 6 before alluded to, to act on the boiler or other element to be heated.

60 By the dual arrangement of the combustion chambers as described, a very high efficiency in combustion of the oil is effected. The burning particles of oil from the expansion chamber by being impinged by the air jets from pipes 17 and 20 against the highly heated arch of the primary combustion chamber, are exploded and broken up as before explained, and the oil in this form and the burning gases flow outwardly through the apertures 30 and 31 and enter the secondary combustion chamber where any particles of the burning oil which may not have been exploded in the primary combustion chamber, will, by striking the highly heated walls and arch of the secondary combustion chamber become completely gasified, thereby eliminating any chance of particles of ungasified oil being deposited on the crown sheet of the boiler or other element to be heated.

70 The primary combustion chamber, due to the formation of its walls of carborundum and due to its communications with the secondary combustion chamber through the multitude of small openings as described, will act as an effective water gas generator, for which purpose water or steam is fed by a pipe 38 to the distributing pan of the burner unit, when by the previous burning of the oil, the carborundum walls of the combustion chambers have become highly heated. The steam passing through the expansion chamber will become superheated by the burning oil, and will be partly dissociated, free hydrogen and oxygen combining with the carbon monoxide to form water gas in the secondary combustion chamber. The dissociation of the steam and cracking of unburned oil are facilitated by the highly heated porous carborundum walls of the combustion chamber. The heat resulting from the combustion of the water gas thus formed, coupled with the heat of the initially burned portion of the oil will give the maximum efficiency at the minimum cost of operation.

80 The two pipes 2 and 38 for supplying respectively the fuel oil and the water or steam to the burner unit, extend downwardly in front of the furnace and enter the front side of the expansion chamber through

the front wall 8 of the furnace structure, the discharge ends of said pipes being arranged over the oil distributing pan 10. The pipe 38 is connected with a suitable source of supply of water or steam as the case may be, and is provided with a controlling valve 40.

The fuel oil supply pipe is likewise provided with a controlling valve 41 and the pipe leads to one end of a stabilizer tank 42 supplied with oil from a pipe 43 entering the other end of the tank. The pipe 43 leads downwardly to the force side of a continuously operating pump 44 driven by a motor 45, which pump has connected with its suction side a pipe 46 leading to a suitable source of oil supply.

The unignited oil flowing from the tray of the burner unit into the overflow tank 26 before alluded to, and accumulating in said tank, is automatically discharged therefrom from time to time by being drawn off by the pump and pumped upwardly into the stabilizer tank to be again supplied to the burner. This is effected by a discharge pipe

47 connected at one end to the pipe 46 and having its other end extended into the overflow tank and terminating near the bottom of the same as shown in Fig. 1. The end of the pipe 47 within the tank is engaged by a valve disc 48 on one end of a horizontal lever 49 pivoted between its ends within the tank on a horizontal transverse axis as at 50, the other end of the lever having fixed to it a float 51. The form and relation of these parts are such that normally the valve disc will be held against and will close the end of the pipe, but on the rise of the float, when the oil in the tank accumulates to a predetermined level, the valve disc will be moved down and will open the end of the pipe, whereupon the pump will act to suck the oil from the tank until the float on descending will raise the valve disc, and again close the pipe, whereupon the oil will accumulate as before and will be again discharged, as described.

Having thus described my invention, what I claim is:

1. In an apparatus of the type described, the combination of a liquid fuel burner unit, means for feeding liquid fuel to said unit, an expansion chamber in position to receive the burning fuel from the burner unit, a primary combustion chamber communicating with the expansion chamber, and a secondary combustion chamber substantially surrounding the primary combustion chamber and communicating therewith.

2. In an apparatus of the type described, the combination of a liquid fuel burner, means for feeding liquid fuel to the same, a primary combustion chamber in position to receive the burning fuel from the burner unit and provided with apertured side walls, an apertured back wall, and a solid arch,

and a secondary combustion chamber substantially surrounding the primary combustion chamber and provided with an apertured back wall and with an apertured arch.

3. In an apparatus of the type described, the combination of a burner unit, means for feeding liquid fuel thereto, an expansion chamber for the burner unit to receive the burning fuel therefrom, a primary combustion chamber communicating with the expansion chamber and provided with apertured side walls, an apertured back wall, and a solid arch to serve as a target for the fuel from the expansion chamber, and a secondary combustion chamber substantially surrounding the primary chamber and provided with solid side walls, and a back wall apertured at a point above the arch of the primary combustion chamber, and an apertured arch.

In testimony whereof I have affixed my signature hereto.

JOSEPH E. RUTTER.
